UNITED STATES PATENT OFFICE.

FRANKLIN S. WILLIAMS, OF BRIDGEWATER, MASSACHUSETTS.

RELEASING DEVICE FOR SHOE RACKS OR CONVEYERS.

1,018,286.

Specification of Letters Patent. Patented Feb. 20, 1912.

Application filed April 8, 1910. Serial No. 554,242.

To all whom it may concern:

Be it known that I, FRANKLIN S. WILLIAMS, a citizen of the United States, residing at Bridgewater, in the county of Plymouth and State of Massachusetts, have invented certain new and useful Improvements in Releasing Devices for Shoe Racks or Conveyers, of which the following is a specification.

10 My invention relates to an improvement in releasing devices for shoe racks or conveyers, and the present invention is an improvement on the invention set forth in application, Serial No. 536,271, filed Jan. 4, 15 1910.

The object of my present invention is to provide a simple means for simultaneously releasing both ends of the trays so that they may be adjusted into a folded position.

20 With these objects in view, my invention consists in certain novel features of construction and combinations of parts which will be hereinafter described and pointed out in the claims.

25 In the accompanying drawings:—Figure 1 is a view in perspective of the lower portion of my rack, showing my improved releasing device attached thereto, Fig. 2 is an enlarged detail of parts of the releasing device, Fig. 3 is an enlarged detail view of one of the casters showing the manner in which the notch engages therewith, and Fig. 4 is an enlarged detail view of the connection between the draw-rod and the catch.

30 35 The frame of the rack comprises two posts or standards 1, 1, and the cross-bar 2. The several racks or trays 3, 3, are pivotally mounted between the posts at their centers, and at each end of the racks or trays, the rods 4, 4, are pivotally connected; and the lower ends of these rods are constructed in the form of catches 5, 5, the ends of which are beveled as at 6, 6, whereby to ride upon the lugs 7, 7, until their notches 8, 8, are 40 45 reached, when the catches spring forward to receive the lug into the notches, thereby locking the racks or trays in a horizontal position. My present invention comprises

a releasing device for simultaneously disengaging these spring catches, and comprises 50 a foot-lever 9 pivotally supported at or near its center 10, at a point at or near the center of the cross-bar 2. Connecting rods 11, 11, extend from opposite sides of the fulcrum, of this foot lever in opposite directions to 55 bell-crank levers 12, 12, pivoted at 13, 13, at or near the opposite ends of the cross-bar, and from the opposite upturned ends 14, 14, of these bell-crank levers, rods 15, 15, extend to the two catches so when it is desired to release the racks or trays, it is merely necessary to force the foot-lever in the direction of the arrow, the effect of which is to simultaneously withdraw the two catches and release them from the lugs, so that the 60 trays or racks may be swung downwardly to their folded position. In this way, a simple and effective means is provided for releasing both ends at one and the same time, thus facilitating the operation of the rack or 70 conveyer, while at the same time employing a simple mechanism for accomplishing the purpose.

It is evident that slight changes might be resorted to in the form and arrangement of 75 the several parts described without departure from the spirit and scope of my invention, and hence I do not wish to limit myself to the exact construction herein set forth, but:—

Having fully described my invention, what I claim as new and desire to secure by Letters Patent, is:—

1. The combination with a base, standards, trays or racks pivotally supported by 85 the standards, and rods pivotally connected with the trays and terminating at their lower ends in spring-catches, of levers pivotally connected to the base of the rack or conveyer, said levers connected to one another, 90 and to the catches whereby the latter may be simultaneously released when the levers are swung in one direction.

2. In a shoe rack or conveyer, the combination with a base, standards or posts, racks 95 or trays pivotally connected between the

posts or standards, rods pivotally connected to the racks, and terminating in spring-catches, of releasing mechanism comprising two bell-crank levers and an intermediate 5 foot-lever, rods extending between said levers from opposite sides of the fulcrum of the foot-lever, and rods extending from the bell-crank levers to the catches, whereby the

two catches are simultaneously operated to release the trays or racks.

10

In testimony whereof I affix my signature, in the presence of two witnesses.

FRANKLIN S. WILLIAMS.
